Primary Examiner — Patricia Palasik(74) *Attorney, Agent, or Firm* — Finnegan, Henderson, Farabow, Garrett & Dunner, L.L.P.(57) **CLAIM**

The ornamental design for a transmission, as shown and described.

DESCRIPTION

FIG. 1 is a front perspective view of a transmission, showing my new design;

FIG. 2 is a front elevation view thereof;

FIG. 3 is a rear elevation view thereof;

FIG. 4 is a left side view thereof;

FIG. 5 is a right side view thereof; and,

FIG. 6 is a top view thereof.

The bottom view is not shown and forms no part of my claimed design.

The broken lines in the drawings depict unclaimed environmental subject matter.
